UNITED STATES PATENT OFFICE.

JOSEPH W. JONES, OF NEW YORK, N. Y.

DESIGN FOR A TACHOMETER-CASING.

53,270.

Specification for Design.

Patented May 6, 1919.

Application filed April 24, 1918. Serial No. 230,590. Term of patent 14 years.

To all whom it may concern:

Be it known that I, JOSEPH W. JONES, a citizen of the United States, and resident of the borough of Manhattan, in the city and State of New York, have invented a new, original, and ornamental Design for a Tachometer-Casing, of which the following is a specification, reference being had to the accompanying drawing, forming part thereof.

My new design for a tachometer casing is shown in the accompanying drawing, in which—

Figure 1 represents the casing in front elevation,

Fig. 2 represents a bottom view of the same,

Fig. 3 represents a side view,

Fig. 4 represents a back view, and

Fig. 5 represents a transverse section taken in the plane of the line V—V of Fig. 1, looking in the direction of the arrows.

I claim:

The ornamental design for a tachometer casing, as shown.

JOSEPH W. JONES.
